UNITED STATES PATENT OFFICE.

EMIL A. DODELIN, OF MOORESTOWN, NEW JERSEY.

CLEANER FOR COMMUTATORS.

Application filed February 24, 1922. Serial No. 539,041.

To all whom it may concern:

Be it known that I, EMIL A. DODELIN, a citizen of the United States, residing at Moorestown, in the county of Burlington 5 and State of New Jersey, have invented new and useful Improvements in Cleaners for Commutators, of which the following is a specification.

My invention relates to a new and useful 10 improvement in cleaners for commutators, and has for its object to provide an exceedingly simple and effective device of this description which may be utilized for intermittently removing lubricant or other foreign substance which tends to accumulate 15 upon the surface of the commutator thereby keeping said commutator in perfect condition.

A further object of my invention is to so 20 construct my improved device that it may be readily applicable to the commutator of any machine either generator or motor.

A still further object of my invention is 25 to provide for automatically presenting a new cleaning surface after each actuation of the device for cleaning the commutator.

A still further object of my invention is 30 to so design the same that it may be operated from any convenient point such as the instrument board of an automobile, while the device itself is so located that it will operate upon the commutator of the generator.

With these and other ends in view, this 35 invention consists in the details of construction and combination of elements herein-after set forth and then specifically designated by the claims.

In order that those skilled in the art to 40 which this invention appertains, may understand how to make and use the same, I will describe its construction in detail, referring by numerals to the accompanying drawings forming a part of this application, in which:—

Fig. 1, is a side elevation of my improved 45 cleaning apparatus in its proper relation to a generator or motor the latter being represented in dotted lines.

Fig. 2, is a rear view of Fig. 1.

Fig. 3, is a detail view of a cushion roll.

Fig. 4, is an enlarged view of the swinging arm of a slightly modified design, one of the side plates being removed and the feed roll being in section.

Fig. 5, is a view of the cleaning rolls 55 looking in the direction of the arrow in Fig. 4.

Fig. 6, is a detail view of a feed roll and the actuating ratchet carried thereby.

In carrying out my invention as here embodied, 1 represents a frame which may be of any suitable size or design and which is intended to be secured upon the base or other convenient portion of an electric motor, generator or like machine using a commutator, such machines being here represented in dotted lines as indicated at 2 the commutator thereof being indicated at 3.

4 represents a swinging arm which while it may be of any design is here shown for 70 the purposes of illustrating this invention as consisting of two side plates secured together by the rivets or screws 5, said rivets or screws serving as pintles or axles for the rollers or shives 6 for the purpose herein- 75 after set forth.

The swinging arm 4 is pivoted between the side plates of the frame 1 by means of the short shafts 7 and 8 and these short shafts are carried by the flanges 9 and 10 80 respectively, said flanges being secured in any suitable manner to the feed roll 11 which latter lies between the side plates of the swinging arm. A ratchet wheel 12 is secured upon the short shaft 7 and a spring 85 pressed actuating pawl 13 engages with the teeth of said ratchet upon one side thereof while a spring pressed running pawl 14 engages with the teeth upon the opposite side of said ratchet in such manner that when 90 the arm 4 is swung back and forth this ratchet wheel will be actuated for the purpose and as hereinafter set forth.

15 represents a cushion roll which may be either made entirely of rubber or partly 95 of a non-compressible material having a rubber or felt rim or in any other suitable manner which will provide for a slight compression of its periphery when contacting with a commutator.

16 represents a supply roll which consists of a coiled strip of sand or emery paper or cloth 17 and is journaled between the extensions 18 of the swinging arm by a removable pin 19 so that when this supply 105 roll is placed in position the strip 17 of which it is composed may be drawn over the shives 6 around the cushion roll 15 and

the free end thereof inserted within the slot 20 of the feed roll and thereafter when the feed roll is intermittently revolved by the swinging of the arm this strip will be drawn 5 forward from the supply roll by being coiled upon the feed roll thus presenting a new surface of said strip upon the cushion roll at each actuation of the arm.

When the device is placed in the proper 10 position relative to a commutator, as shown in Fig. 1, and the arm is swung downward so as to bring that portion of the strip which is then upon the cushion roll into contact with the commutator 3 while the latter is 15 revolving it is obvious that the surface of said commutator will be immediately cleaned of any lubricant or other foreign matter thus overcoming the tendency of said commutator to offer undue resistance to the passage of 20 the electric current or the spark. This downward swinging movement of the arm will cause the pawl 13 to slip over certain of the teeth of the ratchet wheel 12 and when the arm is swung upward this pawl will revolve 25 the ratchet wheel and in so doing draw a new surface of the strip 17 over the face of the cushion roll 15 thereby providing a new surface of abrasive material or contact with the commutator upon the next downward 30 movement of the arm.

In order that the swinging arm 4 may be normally held in an elevated position, I provide a spring 21 one end of which is attached to the extension 18 of said arm, while the 35 other end is attached to any suitable portion of the frame 1.

For the convenient manipulation of the arm a rod, wire or chain 22 is attached to the extension 18 and this rod may be carried 40 to any desired point for the manipulation of the arm at a distance therefrom, as for instance, in an automobile this rod may terminate in front of the instrument board so that the driver of a machine may depress the 45 arm for cleaning the commutator without leaving the seat.

In Figs. 4 and 5, I have shown a slightly modified form of my invention in which two cushion rolls are used each of which is journaled in one end of the equalizing bar 23, said bar being pivoted at 24 in the outer end of the swinging arm 4, in order that the strip 17 may be drawn around these rolls in such manner as to leave a section 25 adapted 55 when coming in contact with the commutator to be flexed to a certain extent thereby bringing the abrasive strip in contact with a greater part of the commutator than would be possible in the construction before described. This modification is especially adapted for use in connection with large commutators.

In practice I have found that this device 60 thoroughly cleans a commutator keeping it 65 in perfect condition for the passage of the

electric current and that it requires only an occasional application of the abrasive material to the commutator which as before described is readily brought about by the depression of the outer end of the arm which 70 when released is returned to its normally elevated position by the spring 21; I have also found that this device is equally applicable to and advantageous for use upon the commutators of all classes of generators and 75 motors, such as those of dynamos, fans, talking machines and the like.

Of course I do not wish to be limited to the exact details of construction as herein shown as these may be varied within the 80 limits of the appended claims without departing from the spirit of my invention.

Having thus fully described my invention, what I claim as new and useful is:—

1. A commutator cleaner comprising a 85 stationary frame, a swinging arm pivoted to said frame, means for swinging said arm manually in one direction, means for returning said arm to its normal position, a compressible roll carried by the outer end 90 of said arm, a supply roll from which a strip of abrasive material may be drawn, said strip passing around the compressible roll, a feed roll with which the opposite end of the strip is attached, and means for intermittently revolving said feed roll from the 95 movements of the arm.

2. In a device of the character described, a frame adapted to be secured in juxtaposition to a commutator, a feed roll journaled between the side plates of said frame, short shafts carried by the feed roll, a swinging arm pivoted to the frame by means of said short shafts, a ratchet wheel secured upon the outer end of one of said shafts, a spring actuated pawl for preventing the revolving of said ratchet wheel in one direction, a second spring pressed pawl pivoted to the arm and adapted to revolve the ratchet wheel in one direction, a compressible roll journaled in the outer end of the arm, a roll of abrasive material mounted upon the arm, guide rolls over which said abrasive material is drawn so as to pass around the compressible roll and be attached to the feed roll in such manner that when the arm is swung upward said abrasive material will be drawn forward by said feed roll to present a new surface upon the compressible roll.

3. A commutator cleaner comprising a frame, a swinging arm pivoted to said frame, guide rolls carried by said arm, a compressible roll pivoted at the outer end of said arm, means for mounting a rolled strip of 125 abrasive material upon the arm in such manner that said strip may be drawn over the guide rolls and compressible roll, a feed roll journaled concentric with the pivot point of the arm and adapted to receive one end 130

of the abrasive strip, and means for revolving the feed roll intermittently by the swinging of the arm.

4. A commutator cleaner comprising a frame, a swinging arm pivoted to said frame, guide rolls carried by said arm, a compressible roll pivoted at the outer end of said arm, means for mounting a rolled strip of abrasive material upon the arm in such manner that said strip may be drawn over the guide rolls and compressible roll, a feed roll

journalled concentric with the pivot point of the arm and adapted to receive one end of the abrasive strip, means for revolving the feed roll intermittently by the swinging of the arm, a spring for normally holding the arm in an elevated position, and means for manually swinging said arm downward against the action of said spring. 15

In testimony whereof, I have hereunto affixed my signature.

EMIL A. DODELIN.
